UNITED STATES PATENT OFFICE.

FREDRIK LJUNGSTROM, OF BREVIK, LIDINGON, AND ISIDOR BROBERG, OF TALLHYDDAN, SKARSATRA, LIDINGON, SWEDEN, ASSIGNORS TO AKTIEBOLAGET LJUNGSTRÖMS ANGTURBIN, OF STOCKHOLM, SWEDEN, A CORPORATION.

COAL BUNKER FOR LOCOMOTIVES.

Application filed November 4, 1921. Serial No. 512,949.

To all whom it may concern:

Be it known that we, FREDRIK LJUNGSTROM and ISIDOR BROBERG, both subjects of the King of Sweden, and residents, respectively, of Brevik, Lidingon, Sweden, and Tallhyddan, Skarsatra, Lidingon, Sweden, have invented certain new and useful Improvements in Coal-Bunkers for Locomotives, of which the following is a specification.

In locomotives it has always proved difficult to arrange coal-bunkers for large amounts of coal and therefore the locomotives and the trains coupled to the same are compelled to stop for a longer time at most stations for coaling than otherwise would be necessary.

Especially it has been difficult to convey a large quantity of coal in case the tender of the locomotive is removed altogether or used for other purposes than that to which it is originally intended, which frequently is the case in locomotives provided with condenser devices, since such devices are generally placed on the tender.

This invention relates to a coal-bunker adapted to increase the store of coal on the boiler-carriage and consists in that the coal-bunker is saddle-shaped and placed above the boiler near the stoker's cabin preferably in front of the same, the coal-bunker being preferably provided with one or more channels extending in the longitudinal direction of the locomotive and facilitating the view from the driver's cabin in the direction of the line.

An embodiment of the invention is illustrated in the accompanying drawing in which—

Fig. 1 shows a boiler carriage of a locomotive constructed according to the invention and Fig. 2 a detail view in section on the line A—A in Fig. 1.

Relating to the drawings, 2 designates the coal-bunker placed above the boiler near the driver's cabin. In the drawing no driving engine is shown on the locomotive, because of the invention being independent of whether the locomotive is driven by means of turbines or provided with piston machinery and whether the driving engine is placed on the boiler carriage or on the following separate machinery carriage. The coal-bunker is saddle-shaped and its fore wall

3 is preferably inclined in such manner that the coal on the emptying of the bunker slides down towards the door provided on the driver's cabin. The coal-bunker extends preferably so far forwards that the steam dome of the boiler can be placed within the same. At the top the coal-bunker is provided with shutters which by means of stirrups 4 are retained in raised position, as shown in Fig. 2, such shutters forming a suitable hopper at the coaling. In Fig. 2 the stippled circle 5 indicates the boiler, said figure besides showing in what manner the coal-bunker in the form shown therein affords larger spaces for coal and how the same may be easily removed and easily fit for coaling. Besides it appears from Fig. 1 how the coal-bunker to decrease the resistance of the air during the journey is constructed as an extension of the driver's cabin and provided with the necessary partition. In such case the coal-bunker is placed in front of the driver's cabin, but it may also be placed behind the driver's cabin in case the latter is mounted at the fore part of the locomotive, if only the bunker is situated near the stoker's cabin.

In order that the view from the driver's cabin may be facilitated in spite of the coal-bunker being located in front of the same, the bunker may be provided with one or more channels 6 extending in the longitudinal direction of the locomotive. As shown in Fig. 2, such channels may preferably be arranged in the two outer sides of the coal-bunker and extend in straight lines towards the fore end of the locomotive from windows 7 on the driver's cabin.

In case the height of the locomotive or the coal-bunker should be so large that the top of the bunker extends beyond the leading gauge, the said top or central part may be omitted.

What we claim as new and desire to secure by Letters Patent of the United States is:—

1. In a locomotive, the combination of a carriage, a boiler supported by said carriage, a cab on the carriage, a saddle-shaped coal-bunker placed on the boiler in front of the cab and extending outside the line of sight from the cab, and channels in the coal-bunker extending from the cab in the longitudinal direction of the locomotive.

2. In a locomotive, the combination of a carriage, a boiler supported by said carriage, a saddle-shaped coal-bunker placed above the boiler, and shutters provided at the top of the coal-bunker and adapted in opened position to form a hopper for the coaling.
3. In a locomotive, the combination of a carriage, a boiler supported by said carriage, a cab on the carriage, a saddle-shaped coal-bunker placed above the boiler in front of the cab and shutters provided at the top of the coal-bunker and adapted in opened position to form a hopper for the coaling.
4. In a locomotive, the combination of a carriage, a boiler supported by said carriage, a saddle-shaped coal-bunker placed above the boiler, and shutters provided at the top of the coal-bunker, and adapted in opened position to form a hopper for the coaling, the fore wall of the coal-bunker inclining downwards towards the rear end of the locomotive.
5. In a locomotive, the combination of a carriage, a boiler supported by said carriage, a cab on the carriage, a saddle-shaped coal-bunker placed above the boiler in front of the cab, channels in the coal-bunker extending from the cab in the longitudinal direction of the locomotive, and shutters provided at the top of the coal-bunker and adapted in opened position to form a hopper for the coaling.
6. In a locomotive, the combination of a carriage, a boiler supported by said carriage, a cab on the carriage, a saddle-shaped coal-bunker placed above the boiler in front of the cab, channels in the coal-bunker extending from the cab in the longitudinal direction of the locomotive, the fore walls of said coal-bunker inclining downwards towards the rear end of the locomotive, and shutters provided at the top of the coal-bunker and adapted in opened position to form a hopper for the coaling.
7. In a locomotive, the combination of a carriage, a boiler supported by said carriage, a cab on the carriage, a saddle-shaped coal-bunker placed above the boiler near the cab, windows in the cab, straightlined channels in the outer sides of the coal-bunker extending from said windows towards the fore end of the locomotive, and shutters provided at the top of the coal-bunker and adapted in opened position to form a hopper for the coaling.

In witness whereof we have hereunto set our hands in the presence of two witnesses.

FREDRIK LJUNGSTROM.
ISIDOR BROBERG.
